UNITED STATES PATENT OFFICE.

JAMES HOTCHKISS AND WM. H. SCHOFIELD, OF YELLOW SPRINGS, OHIO, ASSIGNEES TO
THEMSELVES AND WM. R. KING.

BRICK-MACHINE.

Specification of Letters Patent No. 17,248, dated May 5, 1857.

To all whom it may concern:

Be it known that we, JAMES HORCHKISS
and WILLIAM H. SCHOFIELD, of Yellow
Springs, in the county of Greene and State
5 of Ohio, have invented a new and useful
Improvement in Machines for Molding and
Pressing Bricks; and we do hereby declare
that the following is a full and exact de-
scription thereof, reference being had to
10 the accompanying drawings, making part
of this specification, Figure 1 being a ver-
tical section of the machine in the plane
indicated by the lines *w w*, Figs. 3 and 4;
Fig. 2, a vertical section thereof in the plane
15 indicated by the line *x x*, Figs. 3 and 4;
Fig. 3, a horizontal section of the same in
the plane indicated by the line *y y*, Figs.
1 and 2; Fig. 4, a horizontal section in the
plane indicated by the line *z z*, Figs. 1 and
20 2; Fig. 5, a vertical section at *a a*, Figs. 3
and 4; Fig. 6, a vertical section at *g g*, Figs.
3 and 4; Fig. 7, view in perspective of a
part detached; Fig. 8, a plan of the bottom
25 of the same part; Fig. 9, a diagram show-
ing a modification of the mode of arranging
certain parts.

Like letters designate corresponding parts in all the figures.

The action of the machine is rotary and continuous. The main parts are, a bottom plate D, suitably arranged for supporting the other parts, a horizontal wheel E, in which the driving shaft B, is attached for producing all the movements of the machine, a stationary, top plate C, which covers the working parts, and serves for mounting certain other portions of the machine upon, and a pug mill A, which delivers the clay to the molds. The whole may be constructed of any suitable material, but we contemplate making the machine of cast-iron.

45 The mold wheel E, is of a size suited to the desired capacity and capability of the machine. For making bricks of ordinary size, its rim *c*, is of a width sufficient to allow the length of the mold spaces *d*, *d*, to be formed radially across it, leaving a necessary width of margin at the inner and outer edges thereof, and of proper thickness 50 to form the bricks of the desired thickness, making the proper allowance for the amount of compression to be given to the clay. The molds *d*, *d*, are situated at equal distances 55 from the center of the wheel, and at uni-

form distances apart, there being as many in the whole rim as may be convenient or desirable. A radial arm or spoke, *b*, extends from the rim to the nave of the wheel, centrally opposite to each mold *d*. These arms are thicker than the rim, so as to allow ways, or grooves, *f*, *f*, in the upper and lower sides of each, to be formed for the reception of sliding blocks *G*, *G*, which we denominate the "plunger carriers." These plunger carriers (Figs. 7 and 8) have plane, smooth inner surfaces which slide radially in contact with the surfaces of the rim *c* of the mold wheel; thus closely covering the mouths of the molds *d*, *d*, and a sufficient margin all around, when drawn outward to their full extent. In the under face of each top plunger carrier is situated a plunger *H*, and in the upper face of each bottom plunger carrier is situated a plunger *I*. These plungers fit into cavities in the plunger carriers so that they may sink entirely beneath the surface of the same when desired. Their faces are of the precise shape and size of the molds *d*, *d*, and are brought accurately opposite said molds when the plunger carriers are moved outward to their farthest extent, in order that they may be forced into the said molds, as hereinafter described. The faces of the plungers, as well as the sides of the molds *d*, *d*, are most properly made of steel, so that a proper degree of hardness may be given to them for preventing their wearing away or abrading. They are respectively provided with shanks *h*, *h*, *i*, *i*, fitting in, and projecting beyond, extended bearings in the plunger carriers, substantially as represented in the drawings. The movements of the plungers are communicated thereto by means of these shanks, which, to diminish the friction of contact with the other parts, are, or may be, provided with anti-friction rollers *l*, *l*, in the manner represented.

The movements given to the top plunger carriers are, a radial movement inward, toward the center of the mold wheel, to allow the molds to be filled from the pug mill, and an outward radial movement to bring their plungers over the molds for the purpose of pressing and discharging the bricks, the two movements alternating. The movements given to the under plunger carrier are, a radial movement outward to close the bottoms of the molds for receiving the 100

clay from the pug mill, as well as to hold their plungers to the molds for pressing the bricks, and an inward radial movement, to open the molds, on the lower side, for the discharge of the bricks, the two movements likewise alternating. These movements are effected by the revolving motion of the mold wheel bringing the shanks *h h*, and *i i*, of the plungers, respectively in contact with stationary cams, of the proper forms, on the inner faces of the supporting plates C, D. In Figs. 1, 2, 3, and 4, the cams are represented as being the margins of grooves sunk in the faces of the plates, in which grooves the shanks of the plungers are moved, the groove R, (Fig. 3,) actuating the under plunger carriers, and the groove S, (Fig. 4,) actuating the upper plunger carriers. But we contemplate employing thin plates C, D, to insure lightness, and to secure upon their surfaces separate and adjustable cams, as indicated in Fig. 9, in which the cam S', gives the inward, and S'', the outward, movement to the upper plunger carriers, being secured to the top plate, while the cam R', gives the inward, and R'' and R''' respectively give the outward, movement to, and retain, the plunger carriers in their proper positions, said cams being secured to the face of the bottom plate, D.

At a suitable distance (say one fourth of the circle) from the pug mill A, in the direction of the molding wheel's motion, there are upon, or attached to, the opposite inner faces of the plates C, D, respectively two cams M, N, which are at such distances above and below the molding wheel that when the plungers H, I, of a mold (being, at this part of their circuit, brought exactly opposite the mouths of the mold, by their plunger carriers) are brought between them said plunger will be forced into the mold equally and sufficiently to give the requisite amount of compression to the brick therein, as indicated in Figs. 2 and 6. The lower plunger I falls, by its own weight, from the mold as soon as the cam N, is passed. Farther around in the circle, in the direction of the mold wheel's motion, (say in position opposite to the pug mill,) there is an aperture T, through the bottom plate D, through which the bricks are discharged from the molds. To accomplish this, the bottom plunger I, and its carrier

are first drawn inward, away from the mold, in the manner above described, and then the upper plunger H is forced still farther down in the mold, by a cam L, on the under surface of the upper plate C, as represented in Figs. 1 and 5. The brick in each mold is thus forced out, at the bottom, and falls upon a board, platform, or endless apron, to be removed. A cam, or inclined plane, P, (Figs. 1 and 5,) is arranged so as to receive above its surface the projecting pivot *g*, of the anti-friction roller *z*, in each top plunger shank *h*; as represented, or the projecting edges of the roller itself. Then, as the mold wheel is driven around, the upper plungers are thus raised by said cam P, out of the mold below, and held up till the inward movement of the plunger carrier commences. Thus the movements are repeated, in succession, with each mold in the following order:—First, the upper plunger carrier is drawn inward, and the under plunger carrier outward, for receiving the clay from the pug mill; then, as the wheel passes around, the under plunger carrier remains out, and the upper plunger carrier is forced outward; the pressure is then communicated to the brick by the action of the cams M, N, on the plungers; then the lower plunger descends from the mold, and its carrier is drawn in away therefrom, after which the upper plunger is forced down into the mold by another cam L, till the brick is removed, and finally the said upper plunger is raised out of the mold by another cam P, ready to repeat the operation just described in a succeeding revolution of the mold wheel.

What we claim as our invention is—

The combination of the plungers H, II, 95 and I, I, with the sliding carriers G, G, and mold wheel E, when the same are so constructed and arranged as to operate in relation to each other in the manner and for the purposes set forth.
